UNITED STATES PATENT OFFICE

STEPHEN D. BAKER, OF NEW YORK, N. Y.

DESIGN FOR COMBINATION SOAP HOLDER AND GRAB RAIL

Application filed May 13, 1931. Serial No. 39,832. Term of patent 14 years.

To all whom it may concern:

Be it known that I, STEPHEN D. BAKER, a citizen of the United States of America, and a resident of New York, in the county of New York and State of New York, have invented a new, original, and ornamental Design for a Combination Soap Holder and Grab Rail, of which the following is a specification, reference being had to the accompanying drawings, forming part thereof.

In the drawings:

Fig. 1 is a front view,
Fig. 2 is a side view, and
Fig. 3 a perspective view of a combination soap holder and grab rail embodying my new design.

I claim:
The ornamental design for a combination soap holder and grab rail, substantially as shown.

STEPHEN D. BAKER.
